TO CHARLES S. WALLACE, OF MOREHEAD CITY, NORTH CAROLINA.

SPARK-PLUG.

1,214,401.

Specification of Letters Patent. Patented Jan. 30, 1917.

Application filed June 17, 1916. Serial No. 104,219.

To all whom it may concern:

Be it known that I, ELIJAH J. WILLIS, a citizen of the United States, and a resident of Morehead City, in the county of Carteret 5 and State of North Carolina, have invented certain new and useful Improvements in Spark-Plugs; and I do hereby declare the following to be a full, clear, and exact description of the invention, such as will enable others skilled in the art to which it 10 pertains to make and use the same.

This invention relates to improvements in spark plugs for internal combustion engines.

15 One object of the invention is to so construct the device that it may be readily adapted for use as a priming cup.

A further object is to provide a spark plug construction whereby the firing pin 20 may be quickly removed from the casing of the plug and thus permit the casing to be used as a priming cup.

A further object is to construct the device in such manner that both terminals may 25 be removed from the casing so as to facilitate cleaning of the points without necessity of removing the plug casing from the engine.

A further object is to so construct a spark 30 plug embodying a removable firing pin, that said firing pin can be quickly removed and replaced, and so that when in position in the casing, it shall be so held in place as to avoid possibility of leakage.

35 With these and other objects in view, the invention consists in certain novel features of construction and combinations of parts as hereinafter set forth and pointed out in the claim.

40 In the accompanying drawings, Figure 1 is a view in elevation of the device, with a portion of the cap broken away. Fig. 2 is a view in elevation with the cap removed. Fig. 3 is a vertical transverse section, with 45 the cap omitted, and Fig. 4 is a plan view of the locking sleeve.

1 represents the plug casing having interior flat faces to receive a suitable wrench, said casing being also made with a threaded 50 nipple 2 to enter the plug opening of the engine cylinder. The main body of the casing 1 is made with a cylinder bore which communication with the smaller bore of the nipple 2.

55 A firing pin 3 of suitable nonconducting

material passes through the casing, the lower or inner end of said firing pin preferably being cut-away as shown at 4 adjacent to the exposed portion of the electrical conductors 5, which latter passes through a suitable 60 channel in and is carried by the firing pin. The free end of the conductor 5 constituting one of the sparking points, while the other sparking point is afforded by the projecting end of a conductor 6. This conductor 65 is also carried by the firing pin 3, and passes through a suitable channel in the same as shown in Fig. 1,—the upper end of said conductor being electrically connected with a suitable binding post 7 at the upper end of 70 said firing pin.

The firing pin or insulator 3 is provided intermediate of its ends with an annular flange 8 and the bore of the casing 1 at the juncture of the nipple therewith, is formed 75 with an annular conical shoulder 9.

A yielding washer or gasket 10 is disposed between the annular flange 8 on the firing pin or insulator and the conical shoulder 9 in the casing, said gasket also engaging the firing pin below the annular flange and acting as a packing for the same.

A locking sleeve 11 is located within the plug casing and occupies the space between the upper portion of the firing pin and the 85 inner face of the casing, and between the inner end of said locking sleeve and the flange 9 on the firing pin, a metal washer 12 is located. As washers of this character are well known, they need not be more 90 specifically described or illustrated. The upper end of the conductor 5 terminates at the upper face of the annular flange 8 on the firing pin so as to have electrical contact with the washer 12 and the latter being 95 in electrical contact with the sleeve 11 and casing 1, one side of the sparking circuit will be completed through the engine, as is well understood.

The plug casing 1 is provided at diametrically opposite sides thereof with slots 13 having their upper walls corrugated or roughened. Each of these slots is open at the upper end of the casing and is made with an inclined cam portion 14. The 105 sleeve 11 is provided at diametrically opposite points with arms 15, 15^a to enter the slots 13 and project outwardly beyond the casing sufficient distances to form finger holds or levers to facilitate the manipulation 110

of the sleeve. The upper face of the longer handle 15^a is corrugated or roughened to engage the corrugated or roughened wall of one of the slots and thus prevent the sleeve from slipping. In assembling the parts, the firing pin will first be passed through the casing and then the sleeve will be inserted and turned by means of the arms 15, 15^a—said arms entering slots 13 and, by co-operation with the cam portions 14 of said slots, causing the sleeve to press the washer 12 firmly against the annular flange 8 of the firing pin, and at the same time pressing said flange against the packing or gasket 10. The parts will now be locked together.

In order to protect the upper end of the structure from dust and moisture, I employ a cap 16 which fits over the upper portion of the casing so as to cover the upper end 20 of the firing pin and also the upper edge of the locking sleeve. The cap may be held in place by means of thumb screws 17.

It is apparent that after the cap has been removed, the locking sleeve 11 can be 25 quickly removed by manipulating the arms or levers 15, and then the firing pin together with both sparking terminals may be withdrawn, thus giving such access to said terminals as to facilitate the thorough cleansing of the same. When the locking sleeve and firing pin shall have been removed, the casing 1 will be in free communication with

the interior of the cylinder and may be used as a priming cup.

Slight changes might be made in the details of construction of my invention without departing from the spirit thereof or limiting its scope and hence I do not wish to restrict myself to the precise details herein set forth.

Having fully described my invention what I claim as new and desire to secure by Letters-Patent, is:

A spark plug structure, comprising a plug casing having slots in its wall, each slot 45 open at one end and having a cam portion, the upper walls of the slots being roughened, a removable firing pin passing through the casing and carrying sparking terminals, a locking sleeve for the firing pin located in said casing, said sleeve having arms to pass through the slots in the casing, one of said arms projecting farther beyond the casing than the other and having a roughened upper face, said arms constituting finger pieces to facilitate manipulation of said locking sleeve.

In testimony whereof, I have signed this specification in the presence of two subscribing witnesses.

ELIJAH J. WILLIS.
